REFRIGERATOR CABINET

Guido Maiuri, London, England, assignor to Servel, Inc., New York, N. Y., a corporation of Delaware

Application December 29, 1938, Serial No. 248,165
In Great Britain August 4, 1938

5 Claims. (Cl. 62—89)

This invention relates to refrigerator cabinets primarily but not exclusively intended for the preservation, at sub-atmospheric temperatures, of comestibles or other substances, introduced into the cabinet in an already frozen or cooled condition. For instance already frozen ice cream is preserved in the cabinet at a temperature of from -10° C. to -12° C.

The object of the invention is to provide a refrigerator cabinet which will economically preserve a freezing temperature.

For the above purpose, according to the invention, a refrigerator cabinet is combined with a refrigerating apparatus producing two sub-atmospheric temperatures, and is provided with a heat-insulated refrigerating chamber cooled by the portion of the apparatus producing the lower of the two temperatures, and the wall of the refrigerating chamber is surrounded by a region cooled by the portion of the apparatus producing the higher of the two temperatures.

The cooling at the higher temperature between the atmospheric temperature and the temperature to be maintained in the refrigerating chamber, of the surrounding region economically intercepts part of the heat leaking inwards from the exterior, and thus reduces the amount of cooling to be effected at the lower temperature.

The surrounding region cooled at the higher temperature should be and preferably is itself externally heat-insulated.

A convenient refrigerating apparatus having two evaporators which can be arranged to produce cold at two different temperatures is described in United States Patent No. 2,114,602. This apparatus uses dry ice as the original source of cold and converts the extreme low temperature of sublimation of dry ice into a cooling effect at moderate low temperature. This apparatus has two evaporators in one of which refrigerant evaporates from liquid refrigerant into an atmosphere of the refrigerant, and in the other refrigerant evaporates from a solution of the refrigerant in an absorption medium into an inert gas atmosphere.

It can, for instance, be arranged that the pure refrigerant, ammonia, evaporates under a pressure of 4.4 atmospheres absolute giving a temperature of 0° C. and, the respective evaporator is used to cool the surrounding region. The refrigerant in the other evaporator and which evaporates from the absorption medium, can be arranged to evaporate under a partial pressure of the refrigerant in the inert gas, from 0.25 to

0.45 atmosphere absolute, or less according to the strength of the aqua-ammonia solution, giving a temperature of -20° C., and this evaporator is used to cool the refrigerating chamber to say -12° C. The inert gas for instance is nitrogen and circulates in contra-flow to the aqua-ammonia solution, and in being cooled by the dry ice the ammonia condenses until the partial pressure of the ammonia vapour in the stream of nitrogen is about 0.1 atmosphere absolute.

A refrigerating cabinet arranged and embodying a refrigerating apparatus as above described, is illustrated somewhat diagrammatically in sectional elevation on the accompanying drawing, in which:

a^1 is a refrigerating chamber having a cylindrical metal wall a , surrounded by heat-insulation b . The heat-insulation b is enclosed in a metal wall c , on the outside of which is further heat-insulation d .

The metal wall a of the refrigerating chamber a^1 is embraced by and is in heat-conductive contact with an evaporator e of a refrigerating apparatus.

The outer metal wall c is in heat-conductive contact with a second evaporator f of the refrigerating apparatus, this second evaporator f extending around the inside surface of the wall c .

Refrigerant evaporates in the inner evaporator e at a lower temperature, for instance -20° C., than the temperature, for instance 0° C., at which refrigerant evaporates in the outer evaporator f . The metal wall c cooled by the outer evaporator f , consequently intercepts heat leaking through the outside heat-insulation d , and thus reduces the amount of heat which the inner evaporator e must take up from the metal wall a of the refrigerating chamber a^1 to maintain the contents of the latter at the desired refrigerating temperature.

The refrigerating apparatus shown on the drawing, is of the kind described in United States Patent No. 2,114,602. In the present apparatus, g is a chamber for containing a source of intense cold, such as dry ice, i. e. solid carbon dioxide. This dry ice chamber g is surrounded by a jacket h , embedded in the heat-insulation b , and in which is an upstanding partition h^1 . The jacket h is connected on each side of the partition h^1 , respectively by pipes e^1 , e^2 with different ends of the inner evaporator e . The jacket h , pipes e^1 and e^2 and the evaporator e , contain an atmosphere of inert gas, for instance nitrogen. A strong solution of a refrigerant in an absorption medium, such as aqua-ammonia

liquor, circulates through the evaporator *e*, and from which the refrigerant evaporates under its partial pressure into the inert gas. By convection, the inert gas circulates up the pipe *e*¹ carrying with it the vaporised refrigerant, which latter becomes condensed by the cooling effect of the dry ice and drains into a sump *i*. The inert gas, more or less freed from refrigerant vapour, returns down the pipe *e*² to the other end of the evaporator *e*. The inert gas flows in the evaporator *e* in contra-flow with the refrigerant liquor, strong liquor being supplied to the evaporator *e* by a pipe *j* and impoverished liquor leaving by overflowing a weir *k* into a sump *l*.

The refrigerant liquefied by the cooling effect of the dry ice, flows from the above mentioned sump *i* by a pipe *m* into one end of the outer evaporator *f*. Here the liquid refrigerant is taken up by the capillary action of a metal gauze lining *f*¹, and evaporates.

The refrigerant vapour passes from the outer evaporator *f* by a pipe *n* into an external vessel *o*. The weak liquor from the sump *l* of the inner evaporator *e* flows by gravity, along a pipe *p*, into an external air-cooled vessel *q*. The vessels *o* and *q* are on the same level and are interconnected at the bottom by a pipe *r*, so that the liquor flows from the vessel *q* into the vessel *o*. The refrigerant vapour issuing from the pipe *n* acts as a gas lift on the liquor in the vessel *o* and raises the liquor up a pipe *s* into a more elevated external vessel *t*. The refrigerant vapour passes from the elevated vessel *t* by a pipe *u* into the vessel *q*, wherein it becomes absorbed by the weak liquor arriving by the pipe *p*. The liquor thereby becomes enriched before proceeding by the pipe *r* into the vessel *o*, so that the refrigerant vapour issuing from the pipe *n* is not absorbed in the vessel *o* to such an extent as to prevent it acting as a gas lift in the pipe *s*.

The strong liquor raised to the elevated vessel *t* flows therefrom by a pipe *v* into a heat-exchanger jacket *w* surrounding the weak liquor pipe *p*, and thence by a pipe *j* back to the inner evaporator *e*.

The inner evaporator *e* and the absorber vessel *q* are both lined with wire gauze.

y is a pipe venting the absorber vessel *q* to the inert gas pipe *e*¹ so that when the apparatus is working all inert gas is driven out of the absorber and absorption occurs therein under the total pressure in the apparatus.

The above described dry ice utilising apparatus used to intercept heat leakage and effect direct cooling of a refrigerating chamber for preserving frozen substances frozen, is very economical, as the heat absorbing capacity of the dry ice is almost doubled by the dispersal of heat at super-atmospheric temperature from the absorber of the apparatus.

With an external temperature of +30° C. and a refrigerating chamber *a*¹ to be maintained at -10° C., the intermediate region at the metal wall *c* may be maintained at +5° C. Part of the heat leaking in from outside is absorbed by the outer evaporator *f* from the wall *c* and the remainder by the inner evaporator *e* on the wall *a*

of the refrigerating chamber *a*¹. By increasing the ratio of the thickness of the outer insulation *d* relatively to the inner insulation *b* the intermediate temperature will decrease and vice versa, and consequently the insulation can be proportioned to provide the most convenient distribution of heat absorption between the two evaporators *e* and *f*.

The invention can also be carried out with a diffusion refrigerating machine wherein a refrigerant evaporates into an inert gas under different partial pressures of refrigerant in the gas, giving two temperatures. The evaporator is divided and the inner refrigerating chamber is cooled by the portion of the evaporator working at the lower temperature, whilst the intermediate heat-intercepting region is cooled by the portion of the evaporator working at the higher temperature.

20 I claim:

1. A refrigerator including a thermally insulated storage compartment, a first evaporator arranged to cool said compartment, a second evaporator arranged to cool an insulated zone around said compartment, an absorber connected with said first evaporator for circulation of refrigerant solution therebetween, a conduit for vaporous refrigerant from said second evaporator to said absorber, and a condenser connected to receive vaporous refrigerant from said first evaporator and deliver condensed refrigerant liquid to said second evaporator, said condenser being arranged to be cooled by a primary cooling element such as dry ice.

2. In combination, refrigeration apparatus including a condenser, a first evaporator connected to said condenser, a second evaporator, means interconnecting said second evaporator and said condenser for circulation of inert gas there-through and therebetween, an absorber, means interconnecting said absorber and said second evaporator for circulation of absorption liquid therethrough and therebetween, said system containing a refrigerant fluid soluble in said absorption liquid, a cabinet having a thermally insulated refrigerating chamber, said second evaporator being arranged to cool said chamber, and a thermal conductive medium around said thermally insulated chamber and arranged in heat conductive relation with said first evaporator.

3. The combination as set forth in claim 2 which also includes thermal insulation material around said medium and said first evaporator.

4. The combination as set forth in claim 2 in which said refrigerating chamber is provided with a heat conductive liner and said second evaporator is arranged in thermal conductive relation with said liner.

5. The combination as set forth in claim 2 in which said refrigerating chamber is provided with an inner metal wall, and said medium is an outer metal wall, and said second and first evaporators are arranged in thermal conductive relation respectively with said inner metal wall and said outer metal wall.

GUIDO MAIURI.
